UNITED STATES PATENT OFFICE

MATTHEW GEORGE BURNIS, OF DARTMOUTH, NOVA SCOTIA, CANADA.

FILTER.

1,881,287.

Specification of Letters Patent. Patented Feb. 17, 1932.

Application filed December 8, 1913. Serial No. 335,054.

To all whom it may concern:

Be it known that I, MATTHEW GEORGE BURNIS, a subject of the King of Great Britain, and resident of Dartmouth, in the Province of Nova Scotia, Dominion of Canada, have invented certain new and useful Improvements in Filters, of which the following is a specification.

This invention relates to improvements in filters particularly those of the type used to filter gasolene, and the objects of the invention are to provide a simple and effective filter which will be rapid in operation and in which the several parts will be designed to perform the functions required of them, and it consists essentially of the improved construction hereinafter described in detail in the accompanying specification and drawings.

20 In the drawings:

Figure 1 is a side elevation of an embodiment of the invention.

Fig. 2 is a vertical sectional view.

25 Fig. 3 is a cross section.

In the drawings, like characters of reference indicate corresponding parts in all the figures.

Referring to the drawings. A represents the outer casing or shell, tubular in form and conveniently constructed of sheet metal having screw threaded engagement with a cap 10 at the top and with a sediment container or bulb 11 at the bottom. This sediment container is formed with a conical bottom portion connected to a drainage pet cock 12. The side of the sediment container is provided with a threaded neck 13 to which the supply pipe 14 from the force pump is connected.

30 On the opposite side of the sediment container to that to which the pipe 14 is connected, is connected a return flow pipe 15 of the type usually required by fire underwriters and it is provided with a controlling valve 16.

B represents an inner collecting member extending through the cap 10 which has screw threaded engagement therewith and is also connected by a coupling 17 with a pipe 18 which leads to the delivery hose.

The collecting member B is provided with a plurality of perforations 19 and is closed at the lower end by a cap 20.

C represents a corrugated and perforated sleeve mounted about the collecting member B and spaced a distance therefrom whereby

an annular space will be left between the collecting member and sleeve, the sleeve being formed with a suitable number of perforations 21.

60

On the outer side of the sleeve a tubular straining member D of chamois or the like is provided fitting closely over the supporting member and held at the top and bottom by rings 22 and 23 which hold the straining member and supporting member in engagement with the collecting member B.

It will be seen that the space formed between the supporting member carrying the chamois D and the collecting member B enables the liquid to flow freely away from the filtering surface and provides thereby for a sufficient filtering surface.

It will also be seen that owing to the fact that the supporting member is corrugated, considerable filtering through the chamois member will take place into the corrugation and flow through these corrugations through the perforations to the collecting member B.

The device operates in the ordinary way so the gasolene being forced by the force pump through the pipe 14 filtering through the chamois sleeve D and out through the pipe 18.

It will be seen that by the foregoing construction when the pumping ceases the filter will automatically clean itself of any particles of foreign substance or water which may be clinging to the outer surface of the chamois. These foreign particles or substances will be carried away by the return flow of the gasolene and settle into the sediment bulb 11 at the bottom of the filter.

The filter may be attached to a force pump or the gasolene may be forced therethrough by gravity.

As many changes could be made in the above construction and many apparently widely different embodiments of my invention within the scope of the claims, constructed without departing from the spirit or scope thereof, it is intended that all matter contained in the accompanying drawings and specification shall be interpreted as illustrative and not in a limiting sense.

100

105

What I claim as my invention is:

1. A filter of the character described comprising in combination a casing, a sediment container at the bottom of the casing, a collecting member extending through the casing formed with perforations, a supporting member spaced from the collecting member

110

and being perforated and corrugated, a sleeve of filtering material fitting closely over the supporting member, and means for clamping the sleeve in position.

5 2. A filter of the character described comprising in combination, a tubular casing, a sediment container at the bottom of the casing, a cap at the top of the casing, a collecting member extending through the cap and 10 formed with perforations, a supporting member spaced from the collecting member

and being perforated and corrugated, a sleeve of filtering material fitting closely over the supporting member, and means for clamping the sleeve in position.

In witness whereof I have hereunto set my hand in the presence of two witnesses.

MATTHEW GEORGE BURRIS.
